Primary Examiner — Jeffrey D Asch*Assistant Examiner* — Tracey J Bell(74) *Attorney, Agent, or Firm* — Oppedahl Patent Law Firm LLC(57) **CLAIM**

The ornamental design for a flexible electronic device, as shown and described.

DESCRIPTION

FIG. 1 is a perspective view of a flexible electronic device showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof shown in first bending position;

FIG. 9 is a front view of FIG. 8;

FIG. 10 is a perspective view thereof shown in second bending position;

FIG. 11 is a front view of FIG. 10;

FIG. 12 is a perspective view thereof shown in third bending position; and,

FIG. 13 is a front view of FIG. 12.
